UNITED STATES PATENT OFFICE.

EDGAR H. MAGEE, OF SALEM, OREGON.

FLOOR POLISHER.

Application filed January 18, 1926. Serial No. 32,036.

This invention relates to polishing devices and more particularly to the weighted floor polishing types, the primary object of the invention being to substantially improve and 5 simplify the polishers now upon the market.

In the attainment of this end, there is provided a weighted member, and a shell member for engagement over the weighted member, said shell member serving as a means 10 for clamping the polishing cloth around said weighted member and in order that the edges of the fabric will be housed from view.

An additional and important object is to provide simple means for securing the shell 15 to the weighted member in order that the polishing cloth may be readily removed from and applied to the polishing device.

With the foregoing and other objects in view as the nature of the invention will be 20 better understood, the same comprises the novel form, combination and arrangement of parts hereinafter more fully described, shown in the accompanying drawing and claimed.

25 In the drawing wherein like reference characters indicate corresponding parts throughout both of the views:

Figure 1 is a perspective of my improved 30 polisher.

Figure 2 is an enlarged transverse section through the polishing head and a portion of the manipulating handle therefor.

Now having particular reference to the drawing, my novel polishing device constitutes the provision of a relatively heavy 35 weighted member 5, preferably of rectangular shape as shown, being formed with a marginal flange 6, at the lower edge thereof for providing a shoulder 7 entirely surrounding said member.

Adapted to be stretched over the bottom and sides of the weight 5 is a polishing cloth 8, while adapted to be disposed over the top of the weight is a metal shell 9 of 40 a shape similar to the general shape of the weighted member, the lower edge thereof adapted for rest upon the shoulder 7 for effectively clamping the cloth thereon, as shown in Figure 2.

50 Threaded within the weighted member 5, and extending upwardly therefrom at opposite sides are bolts 10-10 that are also threaded at their upper ends for the recep-

tion of wing nuts 11-11, these elements permitting of the rigid attachment of the shell 55 to the weight.

The shell 9 is provided intermediate the opposite ends thereof with a pair of spaced ears 12-12 intermediate of which is pivotally secured the plate-like end 13 of a 60 manipulating handle 14 for the polisher.

It will thus be seen that I have provided a highly novel, simple, but yet highly efficient form of polishing device wherein the polishing cloth may be removed whenever necessary, and wherein the nature of the polisher is such as to permit of its manufacture at 65 relatively low cost.

Such minor changes may be made as do not depart from the spirit and scope of the 70 appended claims.

Having thus described the invention, what I claim as new and desire to secure by Letters Patent is:—

1. In a polisher of the class described, 75 comprising a weight formed at its lower edge with a marginal flange for providing a shoulder, a polishing cloth adapted to be extended over the bottom and sides of said weight, a shell adapted to be disposed over the top side of said weight for securing the cloth between said shoulder and the edge of 80 said shell and means whereby the shell may be rigidly secured to the weight, and a handle pivotally connected to the shell. 85

2. In a polisher of the class described comprising a weight formed at its lower edge with a marginal flange for providing a shoulder, a polishing cloth adapted to be stretched over the bottom and sides of the 90 weighted member, a shell adapted to be disposed over the top of said weight for securing the cloth between said shoulder and the lower edge of the shell, means for securing the shell on the weight, said means comprising a pair of bolts having their lower ends extending into the top of the weighted member, the upper ends of the bolts extending through the top of the shell, and nuts threaded on the upper threaded ends 100 of the bolts and engaging the top of the shell, and a handle pivotally connected to the shell. 95

In testimony whereof I affix my signature.

EDGAR H. MAGEE,
